(57) **CLAIM**

The ornamental design for a pan cover, as shown and described.

DESCRIPTION

FIG. 1 is a perspective view of a pan cover showing my new design,

FIG. 2 is a top view thereof,

FIG. 3 is a side elevational view thereof,

FIG. 4 is a bottom view thereof,

FIG. 5 is an elevational view of the right end of the pan cover as illustrated in FIGS. 1 through 4; and,

FIG. 6 is an elevational view of the left end thereof.

The broken line structure shown in FIG. 1 is for illustrative purposes only and forms no part of the claimed design.
